J. B. BRADSHAW

SCYTHE FASTENER

Filed Sept. 16, 1924

FIG. 1.

FIG. 2.

FIG. 3.

Inventor

J. B. Bradshaw

John B. Bradshaw
Attorney

234

UNITED STATES PATENT OFFICE.

JOE B. BRADSHAW, OF STANFORD, KENTUCKY.

SCYTHE FASTENER.

Application filed September 16, 1924. Serial No. 738,078.

To all whom it may concern:

Be it known that I, JOE B. BRADSHAW, a citizen of the United States, residing at Stanford, in the county of Lincoln and 5 State of Kentucky, have invented certain new and useful Improvements in Scythe Fasteners; and I do hereby declare the following to be a full, clear, and exact description of the invention, such as will enable 10 others skilled in the art to which it appertains to make and use the same.

The invention relates to fastening means of the nature devised for securing a scythe to the snath and has for its object to insure 15 a firm and positive connection between the blade and handle and to dispense with the use of keys heretofore employed that are liable to get lost and at the same time providing for adjustment of the blade to render 20 the operation of the implement more comfortable and less fatiguing with the result that more work may be accomplished in a given time.

Other objects and advantages will be apparent and suggest themselves as the nature 25 of the invention is understood.

While the drawings illustrate an embodiment of the invention it is to be understood that in adapting the same to meet different 30 conditions and requirements, various changes in the form, proportion and minor details of construction may be resorted to without departing from the nature of the invention.

Referring to the accompanying drawings 35 forming a part of the specification,

Figure 1 is a detail view showing the fastening means for securing a scythe to a snath embodying the invention,

Figure 2 is a sectional view on the line 40 2-2 of Figure 1, and

Figure 3 is a sectional view on the line 3-3 of Figure 1.

Corresponding and like parts are referred to in the following description and designated in the several views of the drawings 45 by like reference characters.

The numeral 10 denotes the snath and 50 11 the scythe which is provided at its heel with the usual tang 12 whereby it may be secured to the snath. In accordance with the invention, the terminal portion of the tang 12 is reduced as indicated at 13, the opposite edges of the reduced portion forming abutments for the inner ends of set

screws 14 whereby the blade is made fast 55 to the snath in the required adjusted position.

Rings 15 and 16 are attached to the blade end of the snath 10 and are held thereto by suitable fastening means such as screws 60 17 and a bolt 18 if need be. These rings are spaced apart and each is provided at one side with a loop or opening 19 to receive the tang 12. The end ring 15 snugly receives the tang 12 and the ring 16 admits of the 65 end of the tang 12 having a lateral movement whereby the angle of the scythe may be adjusted within certain limits as required. Set screws 14 are threaded into opposite portions of the loop or part of 70 the ring 16 provided with the opening 19 so that their inner ends engage opposite edges of the reduced portion 13 of the tang 12 and by properly manipulating the set screws 14 the end of the tang 12 may be 75 adjusted laterally and held in the required adjusted position by turning up the screws 14 so that their inner ends bind against opposite edges of the part 13.

What is claimed is:

1. A scythe fastener comprising rings adapted to be secured to a handle, each of said rings having a second opening therein substantially rectangular in shape and having the plane of one of the walls defining 85 said openings substantially parallel with the axis of the ring, the last mentioned opening in each ring being adapted to receive the tang of a scythe blade, and means associated with one of the rings to secure the tang 90 thereto.

2. A scythe fastener comprising rings adapted to be secured to a handle, each of said rings having a second opening therein substantially rectangular in shape and having the plane of one of the walls defining 95 said opening substantially parallel with the axis of the ring, the last mentioned opening in each ring being adapted to receive the tang of a scythe blade, and means engaging the end walls of the substantially rectangular opening in one of the rings and adapted to engage the tang to secure it in position.

3. A scythe fastener comprising rings adapted to be secured to a handle, each of said rings having a second opening therein substantially rectangular in shape and having the plane of one of the walls defining 100

said opening substantially parallel with the axis of the ring, the last mentioned opening in each ring being adapted to receive the tang of a scythe blade, and set screws engaging one of the rings through the walls defining the ends of the rectangular opening and adapted to engage the tang to secure it in position relatively to the handle.

4. A scythe fastener for a blade having a tang provided with notches in its side edges, comprising rings adapted to be secured to a handle and each having a second opening substantially rectangular in shape and having the plane of one of the walls defining said opening substantially parallel with the axis of the ring, said last mentioned openings being adapted to receive the tang aforesaid, and means engaging one of the rings through the walls defining the ends of the

rectangular opening to engage the notches in the tang.

5. A scythe fastener for a blade having a tang provided with notches in its side edges with inclined shoulders diverging towards the free end of the tang, comprising rings adapted to be secured to a handle and each having a second opening substantially rectangular in shape and having the plane of one of the walls defining said opening substantially parallel with the axis of the ring, said last mentioned opening in each ring being adapted to receive the tang aforesaid, and means engaging one of the rings through the walls defining the ends of the rectangular opening to engage the inclined shoulders in the notches aforesaid.

In testimony whereof I affix my signature.

JOE B. BRADSHAW.
